AUTOMATIC TAPE TRANSMITTER

Edward F. Kleinschmidt, Highland Park, Ill., assignor to Teletype Corporation, Chicago, Ill., a corporation of Delaware

Original application November 1, 1930, Serial No. 492,855. Patent No. 2,000,083, dated May 7, 1935. Divided and this application April 5, 1934, Serial No. 719,104

19 Claims. (Cl. 178—5)

This invention pertains to automatic telegraph systems in which a record is made in directly legible characters by facsimile methods of operation, and relates more specifically to telegraph systems in which each letter or symbol is scanned or analyzed into a succession of constituent elemental areas of positive and negative surfaces.

The present application is a division of application Serial No. 492,855, filed November 1, 1930 by E. F. Kleinschmidt, entitled "Facsimile printing telegraph system and apparatus," which matured into Patent No. 2,000,083, granted May 7, 1935.

An object of this invention is to provide apparatus for the transmission of messages in a system in which the messages are reproduced by facsimile printing receivers and in which proper phase relation of receivers with respect to incoming signals is maintained by start-stop control signals supplied by operation of a controlling transmitter.

A further object is to provide a transmitter for facsimile type transmission, in which prescanning is embodied, and to provide a transmitter which may be started into operation by a keyboard, by a perforated tape control, or by any of the well-known methods of control used in automatic printing telegraphs.

The above and other objects of the invention are accomplished by combining methods which are characteristic fundamentally either of type printing telegraphs or of facsimile telegraphs, in a manner which will affect transmission of code combinations of signal impulses representing a scanning record of individual characters, by providing a preliminary transmitting record in a code simpler than a scanning record, by providing an automatic transmitter which first translates from the simpler code into the scanning code, and by providing novel mechanism details in the automatic transmitter.

The system of the invention is adapted for transmission of a fixed set of characters such as conventional letters and numbers and a high accuracy of scanning is achieved by providing a system of mechanical prescanning, in which first, the total area of a character with its adjacent margins is analyzed into elementary dark and light areas traversible in a sequence, the several elemental areas then being recorded upon a mechanical transmitting member in one form for a dark elemental area and in another form for a light elemental area, the record upon the transmitting member being such in nature that electrical transmission may be effected from it by a

transmitting member having a continuous lineal traversing relative motion. Specifically, a transmitting disc may have projections upon its edge in locations to represent dark areas and notches or absence of projections upon its edge in locations to represent light areas. Such a record member may be revolved with its edge in such relation to an electrical transmitting contact that the contact is closed by the projections to transmit positive current impulses representing the dark elemental areas, and is reversed by the absence of a projection to transmit negative current or no-current representing light elemental areas. A complete set of such record members is provided, and one for each of the characters to be transmitted, after which transmission may be effected by selecting one of said members and transmitting a character under its control, then selecting another of said members and transmitting a character under its control.

Automatic mechanism is provided for rapid and consecutive selection and operation of transmitting record members under control of individual keys in a keyboard or under control of a record tape of any desired form such as a tape perforated with combinational holes in permutation arrangement. For the operation of transmission under control of a perforated tape, feelers are arranged to detect combinational holes in the tape, these feelers are caused to adjust into selective position a set of code bars which control mechanical selection of a desired transmitting disc identified by a combinational arrangement of holes in a controlling tape, and a selected disc member then is caused to transmit the code combination of scanning nature which is recorded upon it. An indefinite length of perforated tape will produce continuous transmission of successive scanning codes of signals, and a novel tape follower mechanism is provided which will interrupt the reading and feeding of the tape when the controlling tape becomes taut.

Selection of a transmitting member and transmission therefrom is effected by providing means for rotating all scanning code members continuously, providing a contact brush for each such member, normally holding the brushes out of contact with the character members, then selecting a brush corresponding to a desired character member, and permitting the selected brush to move into operating contact with its transmitting member. A notch to control transmission of a starting signal in a start-stop system is provided in each character code disc and a disc member similar to a character code disc and with a continu-

ously operating contact brush is provided for transmitting a stop signal between successive character codes. Further, a full disc member adapted to transmit a continuous stop signal or line holding signal is provided with a brush which may be selected in the manner of selecting a brush for character transmission, with an arrangement in the selective mechanism by which the brush for transmitting a line holding signal is selected automatically by the selecting mechanism when controlled by a taut tape mechanism, the transmitter then operating to stop reading the tape, to stop the transmission of character code conditions, and to begin transmission in lieu thereof of a continuous line holding signal or stop signal.

A better understanding of the invention may be had from the following description when taken in conjunction with the accompanying drawings, wherein,

20 Fig. 1 is an elevational and partly sectional view of a transmitter according to this invention;

25 Fig. 2 is a plan view of a portion of the apparatus shown in Fig. 1;

25 Fig. 3 is an end view partly in section of the apparatus shown in Fig. 1;

Fig. 4 is a diagram showing relations between cams in detail of timing, and for transmitted signals;

30 Fig. 5 is a partial plan view taken on line 5-5 of Fig. 1;

Fig. 6 shows a form of perforated control tape which may be used to operate the transmitter;

Fig. 7 shows a transmitting disc adapted for sending character signals;

35 Fig. 7B shows a transmitting disc for sending the stop signal between successive character signals;

40 Fig. 7C shows a transmitting disc for sending a holding signal during periods of suspension of transmission of facsimile signals, and

Fig. 8 shows analysis of a character for scanning, the character there shown corresponding to the disc shown in Fig. 7.

Having reference to Fig. 3, a motor 11 operates shaft 12 to which is secured spiral gear 13 meshed with spiral gear 14 of non-conductive material on one end of code disc shaft 15. Code disc shaft 15 is journaled in bearings mounted in suitable standards or brackets 16, mounted on an insulating plate 18 which is fixed upon the base 17 of the transmitter. The object of the plate 18 is to insulate the shaft 15 from the grounded base 17 because the shaft 15 is in electrical engagement with the code discs which form a part of the electrical circuit of the transmitter.

55 Gear 14 in turn meshes with spiral gear 19 carried on cam shaft 21, journaled in brackets 22, fixed to base 17. Similarly fixed to shaft 21 near the opposite end thereof is spiral gear 23, Fig. 5, adapted to mesh with spiral gear 24 carried on second code disc shaft 25. Shaft 25 is parallel to shaft 15 and likewise is journaled in brackets 26. Shafts 15 and 25 turn in opposite directions to facilitate mounting and operating transmitting brushes.

60 Gears 14, 19, 23, and 24 are so related that the speed of the three shafts 15, 21, 25 is the same. Gears 14 and 24 are insulating in nature 70 to insulate the code disc shafts 15 and 25 from the frame 17.

75 Referring to Figs. 1 and 5, operating shaft 21 carries four cams. Cam 27 draws down the feeler slides 28, of which there are six shown, and releases the slides at the proper time in the

cycle of operation to permit the slides to rise under control of tape 29 as determined by holes in the tape, the slides 28 being sufficient in number to detect all code holes in the tape 29. A suitable six-unit perforated tape of well-known arrangement is shown in Fig. 6.

5 In the present embodiment, the tape, as shown in Fig. 6, has transverse rows of holes 31, each row having six code-hole positions and representing a character or signal. Tape 29 is also provided with a series of feed perforations 31A which cooperate with the teeth of feed wheel 32, Figs. 1 and 3, for advancing the tape in a step-by-step manner. Tape 29 may be prepared by a keyboard perforator or by a receiving perforator of any desired or well-known construction.

10 Cam 27 is engaged by cam follower roller 30 on arm 33 which is integral with and extends from one leg of U-shaped bail 39. A cone 33' extends between and is fixed to, as by brazing or upsetting, the parallel legs of U-shaped bail 39. The cone 33' is drilled through and is carried pivotally together with the bail 39 and integral arm 33 by the shouldered screw 34 which is fixed rigidly in a boss on the bracket 35. Arm 33 has two off-sets 20 oppositely directed, and with bail 39 and cone 33' it forms an integral member having roughly the shape of an arabic numeral "6" as viewed in Fig. 5. Bail 39 normally tends to rotate in a counter-clockwise direction (Fig. 1) under the influence 30 of spring 36 attached to cam follower arm 33 and to spring post 38 fixed in bracket 35. Bail 39 has attached across the parallel legs thereof and near the bases of the legs a U-shaped member 41 which in turn spans and engages all of the lugs 35 42 of the six feeler levers 28 and of a tape slide 43.

25 The leg of bail 39 which is connected to cone 33' at the opposite end from arm 33 is provided with a substantially vertical arm 47 (Fig. 1), the end of which is fashioned for engagement with pawl member 48, loosely mounted on shoulder screw 50 in pivot shaft 49 journaled in bracket 35. Fixed to pivot shaft 49 for rotation therewith and associated with pawl 48 is stop arm 51. Secured to the end of arm 51 is spring post 52 to which is secured one end of spring 53, the other end of which is secured to the end of pawl 48. Thus pawl 48 may be held in operative relation with the arm 47 of lever 33. Engaging faces of members 47 and 48 are beveled to lock against tension of spring 53 except when they are disengaged or unlocked by action of cam follower 30.

30 Referring to Fig. 5, pivot shaft 49 is operatively held in its bearing in bracket 35 by a collar 54 and set screw 55. Pivot shaft 49 is provided near its end with a hole through which tape stop rod 56 is threaded and secured by means of set screw 57. Rod 56 is provided with lateral arm 58 adapted to engage tape 29, which, as it approaches the sender from the right (Fig. 1), passes under arm 55 58 of rod 56, thence through tape guide 59 on guide plate 60 on frame 61 fixed to base 17. Thence tape 29 passes through guide 62 to a receiver for used tape.

35 Thus oscillation of tape rod 56 and its associated assembly of arm 51, etc., is controlled by the alternate tautness and slackness of tape 29. As tape 29 becomes taut, it rotates the tape rod 56 and its associated parts in counterclockwise direction to the full line position of Fig. 1, and thus 70 positions pawl 48 for engagement with coacting arm 47. The resiliency of the spring-held connection between pawl 48 and arm 51 prevents the tape 29 from being strained in case pawl 48 and arm 47 are not in engaging relation. The tape 75

stop arm assembly normally tends to rotate in a clockwise direction due to the over-balancing effect of the stop arm member 56 on the arm member 51. While tape 29 is slack, the tape stop assembly will assume the dotted position shown in Fig. 1, holding pawl 48 out of operative relation with arm 47.

Approximately journaled in mounting frame 61 is shaft 64 (Fig. 1) to which are fixed feed ratchet wheel 46 and feed or sprocket wheel 32. The tape guide 59 is slotted to permit the teeth of sprocket 32 to extend through to engage feed holes 31A (Fig. 6) of tape 29.

Suitably mounted near the top of tape feed lever 43 (Fig. 5) is tape feed pawl 45 (Fig. 1), which coacts with tape feed ratchet 46 to effect rotation thereof in a step-by-step manner, thus imparting similar rotation to shaft 64 and feed or sprocket wheel 32. Pawl 45 is spring-pressed against the ratchet 46 by a suitable spring 66. Appropriately mounted in frame 61 and in cooperative relation with ratchet 46 is detent member 67 with detent roller 68 and spring 69.

Positioned in slide guides 71 and 72 of mounting frame 61 are feeler slides 28 (of which there are six in the present instance) and tape feed slide 43, said slides being held in the grooves by retaining plates 73 and 74. Each of said slides 28 and 43 is provided with its individual spring 75, each spring extending from a lug 76 on its associated lever to common spring bracket 77 (Fig. 3) fixed to cross tie 78 of mounting frame 61. Said levers 28 and 43 thus are urged upwardly by their springs 75 unless prevented by yoke member 41 upon follower lever 33.

Each feeler slide 28 is provided with its individual feeler pin 79 in the upper end of each slide and cooperates with code perforations 31 in tape 29, and similar holes in tape retaining member 81 hinged at the side of tape guide 59, as shown in Fig. 3. Member 81 is provided with a suitable latch 82 adapted to hold said member down with block 81 entering between flanges on tape guide 59. Thus, when cam follower roller 30 of follower lever arm 33 is in contact with the low part of cam 27, the follower lever arm assumes its counterclockwise position due to the action of spring 36, and accordingly member 41 assumes its uppermost position. The feeler slides 28 then are free to move upwardly due to the tension of their individual springs 75. However, only those slides 28 will move whose individual feeler pins 79 have found a code perforation 31 in the tape 29.

Simultaneously tape feed slide 43 carrying tape feed pawl 45 is also permitted to assume its uppermost position such that pawl 45 is permitted to engage the next tooth of ratchet 46 preparatory to effecting the rotation of ratchet 46 one step, which rotation will be effected by the downward movement of tape feed slide 43, when follower lever arm 33 again moves clockwise which occurs when the follower roller 30 again is engaged by the high part of the cam 27.

Each feeler slide 28 is also provided with its stop lug 83 adapted to cooperate with a testing finger 84 on the end of transfer levers 85 which are equal in number to the tape feeler slides 28 to which they correspond severally. The six transfer levers 85 are pivotally mounted independently upon common pivot shaft 86 suitably held in a pair of brackets 87 integral with mounting frame 61.

Each transfer lever is provided with a lug 88 to which is secured one end of an individual

spring 89, the other end being connected to an adjusting screw 91. Transfer levers 85 thus normally tend to rotate in a clockwise sense due to the action of their individual springs 89. Each transfer feeler 85 is also provided with a reset 5 lug 93 and power lug 94.

Reset lugs 93 (six in number in the present instance) are spanned by reset bail arm 95 of the transfer feeler reset bail lever 98, pivotally mounted at 97 on bracket 35, and carrying cam 10 follower roller 99 adapted to engage the periphery of reset cam 101 due to spring 102, secured to bail arm 95 and to spring post 103 fixed to bracket 35. Cam 101 is fixed upon shaft 21.

Cam follower roller 99 normally engages the 15 high part of cam 101, thus maintaining reset bail 95 in its extreme clockwise position, as shown in Fig. 1, against the action of spring 102. Bail arm 95 by its cooperation with reset lugs 93 thus normally holds transfer levers 85 in 20 their counterclockwise position against the action of individual springs 89 and away from lugs 83, to permit the free operation of the feeler slides 29. Therefore, when cam follower roller 99 engages the low part of reset cam 101, reset 25 lever 98 will rotate in a counterclockwise sense under the action of spring 102, thus rotating bail arm 95 out of operative engagement with reset lugs 93 of transfer levers 85, which then are 30 free to rotate in a clockwise sense due to the action of their individual springs 89 unless prevented by associated stop lugs 83 of feeler slides 28. That is, if a feeler slide 28 has been permitted to rise due to finding a perforation in the tape, its stop lug 83 will have been raised 35 out of the path of testing finger 84 of transfer lever 85. Conversely, if a feeler slide 28 fails to rise, associated testing finger 84 will engage the interposed stop lug 83 and prevent its transfer lever 85 from rotating. When reset lever 98 resumes its clockwise position, bail arm 95 will 40 again engage reset lugs 93 and restore transfer levers 85 to their normal counterclockwise position.

Each transfer lever 85 is also provided with its 45 individual power lug 94 adapted to cooperate with the end of a permutation bar 104, the number of which is equal to the number of transfer feeler levers 85; namely, six in this instance.

Permutation bars 104 comprise flat strips set 50 on edge and guided at each end in slide guides 105 integral with permutation bar guiding unit 106 which is attached to base 17. Each permutation bar thus is moved endwise. The top edge of each bar is provided with a series of notches 55 arranged according to the permutations of the signal code. The notches in permutation bars 104 are so arranged that for every combinational setting of the bars, only one complete alignment of notches is effected. Each permutation bar 60 104 is adapted to assume two positions. Its normal position is to the right (Fig. 1), to which position each bar is urged against its associated power lug 94 by tension of its individual spring 107. Its operated position is to the left by a determined distance, to which position it is urged by its associated power lug 94, propelled by spring 89. Springs 89 and 107 have strength such that spring 107 may move bar 104 to the right, and such that spring 89 may produce upon bar 104 70 a power double that of spring 107, being thus able to overcome spring 107 and move bar 104 to the left.

Each permutation bar 104 is provided near its right end with two V-shaped notches 112, adapt- 75

ed to cooperate with permutation bar locking or 5
detent lever 113 pivotally mounted at 114 on bracket 35. Lever 113, urged by spring 115, constantly tends to rotate in a clockwise sense into operative relation with the notches in permutation bars 104. The other end of lever 113 is provided with cam follower roller 116 engaging the periphery of permutation bar detent cam 117. Cam 117 forces lever 113 in a counterclockwise 10 direction against the action of spring 115 so as to disengage from notches 112 for a brief interval to permit permutation bars 104 to be reset in accordance with a new combination.

Associated with permutation bars 104 are eligible units 131 (Figs. 1 and 3) one such unit being provided for each character to be transmitted and hence one for each setting of the notches of the permutation bars. Referring to Fig. 3, the units 131 are pivotally mounted on a pair of pivot 20 shafts 122 and are alternately arranged on either side of permutation bars 104. Said pivot shafts 122 are mounted in suitable brackets 123 fixed to base 17. Each unit 131 comprises a bell crank lever, the substantially horizontal arm 125 of which is provided at its end with a stem portion 126 carrying a series of small rollers 127 which cooperate with the permutation bars 104. Stem portions 126 of units 131 are guided for vertical motion in slots of the pair of comb bars 128 secured to the sides of permutation bar guide 106. Attached to the free end of each stem 126 are springs 129, the other ends of which are attached to the bottom of comb bar 128. Thus springs 129 tend to draw arms 125 of units 131 against the 35 six permutation bars 104.

Each unit 131 carries at its upper end the insulation 132 and screw 133 which clamp brush 134. Brush 134 cooperates with code discs 135 carried by shafts 15 and 25. Discs 135 are mounted 40 tight upon their respective shafts 15 and 25 and are spaced by conducting collars 136 which connect all discs electrically to the feed disc 141 at the end of each shaft 15 and 25. Discs 137 of insulating material are also placed between code discs 135 to prevent brushes 134 from dropping deeply into the notches of the discs 135. All discs are positioned by rod 138 in proper angular relation and clamped together so that all discs 135 may rotate as a unit.

Each such code disc has associated with it an individual brush 134 with its operating eligible member 131. All brushes 134 are connected to a common wire 139 (Fig. 2) and all code discs 135 are connected through shafts 15 and 25 and 55 through the end disc 141 (Fig. 1) to the common wire 142 (Fig. 2), the brush for disc 141 always engaging with unnotched surface of the disc. The wires 139 and 142 form the output circuit of the transmitter. Each code disc 135 has a high 60 radius 143 at each point where a signal is to be transmitted, thereby connecting the wires 138 and 142 at such times.

When the series of notches in permutation bars 104 pertaining to an eligible unit 131 are aligned, 65 the selected unit 131 will be rotated slightly as the stem portion 126 with its associated rollers is drawn into the aligned notches by its individual spring 129. Thus brush 134 individual to the selected unit 131 will be rotated into engagement with its associated code disc 135. All code discs 135 are constantly rotating and the selection of a unit 131 and the contact of its associated brush 134 and code disc 135 are properly timed 70 so that said contact will always occur at the prop-

er point on the periphery of the code disc, as described hereinafter.

Located below the stem portions 126 of the units 131 and guided in the permutation bar guide 106, is bail blade 145 (Figs. 1 and 3) which is elevated to raise the selected unit 131 out of the aligned notches and further to lift all units free from the bars 104 preparatory to the shifting of the permutation bars 104 in accordance with a new combination. Pivots connected to downward lugs 146 on bail blade 145 are a pair of bell crank levers 147 pivotally mounted in base 17. The other arms of bell crank levers 147 are pivotally connected to connecting link 148, one end of said link 148 being extended to pivotally connect with arm 149 of bail operating lever 151. Bail operating lever 151 is pivotally connected to permutation bar guide 106. Carried on lever 151 is cam follower roller 152 engaging bail operating cam 153 on shaft 21. Bail blade 145 normally 20 assumes its downward position as shown in Figs. 1 and 3 due to the tension of spring 154, attached to one of the bell crank levers 147 and to base 17.

Referring to Figs. 7 and 8, code discs 135 are designed according to a method of prescanning. 25 The character to be transmitted is divided into any desired number of transmitting units of area. The several units of each character thus created are assigned in sequence to the edge of the disc 135 individual to that character, in the order of scanning, and the dark units are made of high radius to engage the brush 134 to send a signal.

This method of and apparatus for prescanning each character and providing an electrical transmitting element in accordance therewith is described and claimed in Patent No. 2,000,083, granted May 7, 1935.

For an example of prescanning, the letter "R" is shown in Fig. 8 together with the blank area between the letter and the preceding letter. It is 40 preferred to leave a blank interval also below the letter so that when the letters are printed in rows one above the other, there will be a space or a white line between the rows. This total area is divided into 450 units of area, 25 high and 18 45 wide. Its corresponding code disc is shown in Fig. 7.

Scanning begins at the unit 155 (white) and progresses vertically to the unit 156, continuing immediately at unit 157, again at unit 158, and again from unit 159 to 161, completing the scanning of 78 successive white units, resulting in the low radius arc 162 on the disc 135 of Fig. 7. The scanning of black units extends from unit 163 to unit 164, resulting in the high radius arc 165. Then the three white units 166 to 167 result in the low arc 168 and the 22 black units 169 to 171 result in the high arc 172. Continuing in like manner, scanning of the total area of Fig. 8 results in the total arcs on the edge of disc 135 60 of Fig. 7.

Code disc 135 represents the letter "R." Other code discs shown in Fig. 2 represent other characters. Every character code disc has the initial starting arc 162 of Fig. 7, and all starting arcs 162 65 are arranged in alignment.

In Fig. 7C is shown a code disc 181 having a continuous high edge. This is the disc for the line-holding signal or idle-line signal. The brush 134 is shown movable for selection.

In Fig. 7B is shown a code disc 183 having a high edge, of 50 degrees of angle. This is the disc for the stop signal. The brush 184 for the disc 183 solely is shown fixed and not movable for selection.

Having described in detail the construction of the transmitting apparatus, a description of the general operation of the transmitter will be given.

The transmitting apparatus is started in operation by closing the circuit to the motor 11, thus causing the shafts 15, 21, and 25 to be rotated at the same speed. The speed of the motor 11 may be governed as shown in Patent No. 2,000,083 of record above.

10 Perforated tape 29 is properly engaged with the feed wheel 32 whereby the tape will advance in step-by-step manner toward the left of the apparatus as viewed in Fig. 1.

15 Transmission of signals is controlled by the slackness or tautness of the tape, whereby operation of the transmitter is suspended when the feed of the tape is stopped or slowed down, and the slack is taken up by continued operation of the transmitter. For example, if a keyboard perforator is being used to perforate directly the 20 tape, there will be slack in the tape and the lever 56 will assume the dotted line position (Fig. 1) before transmission will start. If the perforator is operated faster than the transmitter operates, 25 the loop in the tape, or the slack, will increase and the transmitter will continue to operate. If the tape is perforated slower than the transmitter operates, or if perforation stops, the slack 30 in the tape will be gradually taken up by the transmitter until the tape becomes taut. This tautness of the tape will move the bar 56 to the 35 full line position shown in Fig. 2, thus moving the lever 51 downwardly and carrying the latch 48 into the path of movement of arm 47 on lever 33.

Therefore, upon the next counterclockwise movement of lever arm 33 under action of its spring 36 after the tape tightens, when the roller 30 thereof leaves the high portion of its cam 27, 40 arm 47 carried by bail 39 will be latched by the latch 48 and transmission of signals will be suspended, since U-shaped member 41 carried by bail 39 cannot rise to release feeler slides 28. With the parts in this position, the motor and the driven cam shaft 21 continue to rotate but 45 the feeler slides 28 are not allowed to rise and therefore there is no new selection of a character.

Whenever receiving apparatus operates on the start-stop principle, it is necessary that the transmitter be arranged to transmit start-stop signals to operate receivers properly. Therefore, the transmitter is arranged to operate the start-stop receivers by the following mechanism.

In Fig. 7C, the code disc 181 effects an idle-signal condition at the receiver. Its brush 184 is selected and is operated against the disc 181 whenever all permutation slides 104 are at the right in Fig. 2, a selection which is produced either by detaining the arm 47 by the latch 48, 55 thus holding down all of the slides 28 by the bail 41, or by a non-perforated tape which likewise will hold down all of the slides 28 and estop the action of all transfer levers 85.

In Fig. 7B, the code disc 183 sends the periodic stop and start signals. Its brush 184 is not subject to selection and the disc 183 makes engagement with the brush 184 at every revolution.

When disc 181 is selected, there will be no start signal, since discs 181 and 183 effect continuous contact between wires 142 and 138 of Fig. 2. Should disc 135 be selected repeatedly, the 60 degrees low arc of disc 135 will be occupied by disc 183 which will send a marking signal of 50 degrees for stop and then a spacing signal of 10 degrees for start. The angles may be varied

as desired in any specific embodiment of this invention.

Assume that tape 29 is engaged with feed wheel 32, that the tape is taut to engage latch 48 with arm 47, holding the bail 41 down and the follower 50 up, that motor 11 is running and is driving cams 27, 101, 117, 153, and also driving all of the code discs. Disc 181 is selected by the position of slides 28. Brush 184 engages disc 181 through 310 degrees or more and brush 184 engages disc 183 through 50 degrees and a continuous marking signal is transmitted. The mechanical actions are the repeated engagement of cam 27 with cam roller 30 once each revolution of shaft 21, each such engagement acting to lift 10 arm 47 briefly from latch 48, and the repeated lifting of the brush 184 from disc 181 by cam 153 and bail blade 145. This would interrupt the transmitter current but the break is closed by disc 183 and fixed brush 184.

20 The middle point of the period of engagement of cam 27 and roller 30 will be taken arbitrarily as the zero angle from which a cyclic study of operation will be made. The shaft 21 and cams in Fig. 1 are shown about 50 degrees before this 25 zero angle occurs. The timing chart of Fig. 4 shows two cycles of lapsed time. The line 185 indicates the electrical signal as transmitted to the line circuits over wires 139 and 142.

Should a supply of perforated tape be made 30 available, as by beginning operation of a tape perforator, the arm 56 will be freed from the tape and by its weight will lift arm 51 slightly, placing a tension upon spring 53 tending to lift latch 48. At the next zero angle, say the third 35 zero in Fig. 4, arm 47 will release latch 48 to clear the pathway of arm 47, thus liberating the cam follower arm 33. The release of arm 47 from latch 48 cannot take place until cam 27 and roller 30 act to rotate lever arm 33 clockwise, 40 thus preventing the skipping of a combination in the tape 29.

The passing of the apex of cam 27 permits slides 28 to rise when holes are found in tape 29. Cam 101 then permits transfer arms 85 to rotate 45 where feelers have risen. Lugs 94 push against permutation bars 104 which are held locked by bail 113. Cam 163 then operates bail 145 to lift all members 125 and cam 117 operates bail 113 to unlock permutation bars 104 briefly, permitting 50 transfer levers 85 to operate permutation bars 104 corresponding to holes found in tape 29. Cam 153 permits bail 145 to descend to effect selection of a code disc; cam 101 permits bail 95 to descend to restore the transfer members; cam 55 27 forces bail 41 down to restore the feelers and to step the tape 29. The bail 145 lifts all brush levers 131 from the discs during the time that transfer levers 85 are against the bars 104.

The line signal during the third cycle of Fig. 4 60 is holding signal (marking) by disc 181 to angle 155 degrees, then stop signal (marking) by disc 183 to angle 205 degrees, at which point a spacing signal is sent for 10 degrees to start the remote receiver. The character code is sent from angle 65 215 degrees to angle 155 degrees of the next cycle, when the stop signal by disc 183 begins again.

In two successive codes where a bar 104 is set to the left by spring 89 for the first code and is required to be reset to the right for the second, 70 the feeler slide 28 will not rise on the second code, the transfer lever 85 will not rotate on the second code, and when the locking edge 113 is lifted by cam 117 and follower roller 116, the bar 104 will be drawn to the right by power of the spring 75

107, the bar 104 being stopped in correct position by engagement with its controlling lug 94.

As explained in connection with Figs. 7 and 8 there is provided an initial blank or non-contacting segment on each disc corresponding to blank spaces of Fig. 8 from point 155 to 159, or referring to Fig. 7, corresponding to the non-contacting segment 162. As the discs 135 revolve, signals are transmitted over the outgoing lines in accordance with a scanning of the selected character. However, due to the novel arrangement of providing an electrical contacting segment whose contact portions and non-contact portions correspond to the dark and light areas of the character, actual transmission of signals may take place at a much higher speed than any true scanning operation could transmit corresponding impulses, and therefore transmission of the characters is much more rapid than could be obtained by a scanning operation.

Another important feature of this invention which contributes to the high speed of operation thereof is the overlap whereby transmission of a selected character may be carried on during the period that a subsequent character is being selected and the mechanical parts corresponding to the subsequent character are being positioned to select said character. This is true because the selected unit maintains its contact brush 134 in contacting position during one revolution of the shaft 21, during which the parts are being positioned for the next character.

As previously described, if the tape 29 has become taut due to transmission having been suspended, the latch 48 will engage arm 47 of bail 39 and retain the feeler slides 28 in their downward position.

This returns the mechanism to the initial position, and the parts pass through the same cycle as above described, to thus successively select holding disc 181 by engaging its individual brush 134 therewith, as long as no tape 29 is fed to the transmitter.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed is:

1. In a telegraph transmitter, a plurality of transmitting members each having elements for transmission of signals for one character, means for selecting said members by control of performances in a tape, a cyclic cam shaft, and means for controlling the operation of said transmitter by tension of said tape jointly with said cam shaft.

2. In a telegraph transmitter, a plurality of transmitting members each having elements for transmission of signals for one character, a cyclic cam shaft, and means controlled by cam followers and operable once in each cycle of said shaft for selecting one of said transmitting members and for transmitting therefrom.

3. In a telegraph transmitter, a plurality of tape controlled feeler fingers, a plurality of code signal transmitting elements each adapted to transmit a code signal of one character, means for periodically controlling the selection of a transmitting element by said feeler fingers, a

further transmitting element, and means controlled by the tension of said tape for controlling the selection of said further transmitting element.

4. In a telegraph transmitter, a plurality of transmitting elements arranged in two symmetrical sets, a plurality of permutation bars, a plurality of detector levers controlled by said permutation bars and adapted to control said transmitting elements, and a resetting bail for said detector bars and positioned between said permutation bars.

5. In a telegraph transmitter, a plurality of permutation bars, a plurality of transmitting elements arranged symmetrically on both sides of said permutation bars, and a plurality of detector levers adapted to be controlled by said permutation bars and to control said transmitting elements, alternate ones of said detector levers being pivoted on opposite sides of said permutation bars.

6. In a telegraph transmitter, code transmitting members variably adapted each to transmit a complete code signal, means for selecting said members, a recurrently operating transmitting member and means for operating one of said code transmitting members between successive operations of said code members.

7. In a telegraph transmitter, a plurality of transmitting members each adapted to transmit a complete code signal, selectively adjustable contactors for said members, a further transmitting member and a fixed contactor for said further transmitting member, and means for operating said fixed contactor alternately with selected ones of said adjustable contactors.

8. In a telegraph transmitter, a first transmitting element, a plurality of eligible code transmitting elements shaped to represent a code signal, a further eligible element shaped to represent a holding stop signal means for selecting one only from all of said eligible elements and means for operating selective ones of said eligible elements consecutively with respect to each other and alternatively with respect to said first element.

9. In a telegraph transmitter, a record tape controlled selecting mechanism, tape tension responsive means for controlling said selecting means, a first transmitting element shaped to transmit a single signal impulse, a plurality of eligible transmitting elements shaped to transmit a code signal, a further transmitting element, means under control of a record tape for selecting one of said eligible elements, and means under control of said tape tension responsive means for selecting said further transmitting element.

10. In a telegraph transmitter having a cyclic operation comprising three successive time periods, a transmitting element shaped to transmit invariably a signal during the first period of every cycle, a plurality of selectable transmitting elements shaped to transmit a code signal during the third period of any cycle, a selectable transmitting element shaped to transmit a continuous signal, means to operate said first mentioned element repeatedly, means to select and operate ones of said selectable elements and to transmit from said selected elements in alternation with transmission from said first mentioned element, and further means to select said last mentioned transmitting element and to transmit therefrom continuously.

11. In a telegraph transmitter having a cyclic operation comprising three successive time pe-

riods, a tape controlled selecting mechanism, tape tension responsive means for controlling said selecting means, a transmitting element, a plurality of selectable transmitting elements, 5 means to operate said first mentioned element invariably, means under control of a record tape for operating certain of said selectable elements, and means under control of said tape tension responsive means for operating a particular one of 10 said selectable elements.

12. In a telegraph transmitter, a tape controlled selecting mechanism, a tape tension responsive mechanism, a contact operable independently of said selecting mechanism for transmitting 15 a recurrent signal, a contact operable selectively, and means controlled by said tape tension responsive mechanism to operate said selectable contact to transmit a continuous signal.

13. In a telegraph transmitter, a plurality of 20 elements each individually for sending a complete code signal, a further element for sending an idle-line signal, means for selecting one of said elements in response to records in a tape, 25 and means for controlling the selection of said further element in response to the tension of said tape.

14. In a telegraph transmitter, a plurality of 30 transmitting elements for transmitting code signals, a further transmitting element for transmitting an idle-line signal, feeler pins for detecting perforated codes in a tape, means for selecting ones of said transmitting elements and for transmitting code signals consecutively in 35 response to perforated codes in said tape, and means to select said further element when said pins detect no code in said tape.

15. In a telegraph transmitter, a plurality of transmitting elements each individually for transmitting a complete character code signal, a further transmitting element for transmitting an idle-line signal, feeler pins for detecting perforated codes in a tape, means to select one of said transmitting elements in response to said feeler pins and for transmitting code signals from selected ones of said elements, and further means to select said further transmitting element in response to the tension of said tape and to transmit an idle line signal therefrom. 10

16. In a telegraph transmitter, a code transmitting mechanism, a locking latch for disabling said code transmitting mechanism, a cyclic cam, 15 a cam follower to unlock said latch at every cycle of said cam, and means for unlatching said transmitting mechanism and operable during the period that said latch is unlocked by said cam.

17. In a telegraph transmitter, a cam, a tape 20 controlled mechanism, and a latch to disable said mechanism conditioned directly by the tension of the tape and rendered effectual by said cam.

18. In a telegraph transmitter, a tape controlled mechanism, a bail to disable said mechanism, a cam controlling the position of said bail, and a tape controlled arm effective on said bail 25 jointly with said cam.

19. In a telegraph transmitter, a tape controlled mechanism including a plurality of sensing fingers, a bail operative on said fingers, a cam controlling the position of said bail, and a tape controlled arm effective on said bail jointly with said cam for controlling the operation of said fingers. 30

EDWARD F. KLEINSCHMIDT. 35

CERTIFICATE OF CORRECTION.

Patent No. 2,126,397.

August 9, 1938.

EDWARD F. KLEINSCHMIDT.

It is hereby certified that error appears in the printed specification of the above numbered patent requiring correction as follows: Page 3, first column, line 8, for the word "Approximately" read Appropriately; page 6, first column, line 73, claim 3, for "of" read for; and that the said Letters Patent should be read with this correction therein that the same may conform to the record of the case in the Patent Office.

Signed and sealed this 14th day of February, A.D. 1939.

Henry Van Arsdale.

(Seal)

Acting Commissioner of Patents.
